UNITED STATES PATENT OFFICE.

JOHN M. EWEN, OF CHICAGO, ILLINOIS, ASSIGNOR TO THE LUXFER PRISM PATENTS COMPANY, OF SAME PLACE.

DESIGN FOR A PRISM-LIGHT.

SPECIFICATION forming part of Design No. 27,337, dated July 13, 1897.

Application filed June 15, 1897. Serial No. 640,937. Term of patent 14 years.

To all whom it may concern:

Be it known that I, JOHN M. EWEN, a citizen of the United States, residing at Chicago, in the county of Cook and State of Illinois, have 5 invented and produced a new and original Ornamental Design for Prism-Lights, of which the following is a specification.

My invention relates to a new design for prism-lights and is illustrated in the accompanying drawings, wherein—

Figure 1 is a plan view, and Fig. 2 a section through the same.

Like parts are indicated by the same letter in each of the figures.

5 A is the body, and B one of the prisms

thereon. The body is substantially octagonal in form, and the prisms are placed on one side thereof parallel with one edge.

The essential features of my invention are found in a prism-light having a body of a 20 substantially octagonal form with a series of prisms running across one side thereof parallel to one edge.

I claim—

The design for a prism-light substantially 25 as shown and described.

JOHN M. EWEN.
